MICROTOME KNIFE

George W. Jacoby, Jr., Wooster, Ohio

Application August 17, 1950, Serial No. 180,067

6 Claims. (Cl. 88—40)

1

This invention relates broadly to microtomes and more specifically to improvements in knives and knife holders therefor.

One of the objects of this invention is to provide a knife holder for a microtome capable of maintaining a knife rigidly affixed thereto.

An important object of this invention is to provide a knife holder which will permit lateral adjustment of the knife relative to a mounted specimen in the microtome without disturbing the preadjusted position of the knife holder.

Another object of this invention is to provide shoulders on the back of the cutting blade for engagement by operable parts on the knife holder which releasably affix the knife in its operating position.

A further object of this invention is to provide a microtome blade support which is rigid and stable during operation and which may be readily positioned for trimming and finishing while retaining cutting adjustments.

Further objects of this invention reside in the provision of a knife and holder which are sturdy of structure, economic of manufacture, efficient of operation, and an assembly which is susceptible of use on existing machines without modification thereof.

Other objects and advantages, more or less ancillary to the foregoing, and the manner in which all the various objects are realized will appear in the following description, which, considered in connection with the accompanying drawings, sets forth the preferred embodiment of the invention.

Referring to the drawings:

Fig. 1 is a view in perspective of a microtome embodying the invention;

Fig. 2 is a view in perspective of the improved knife and holder therefor;

Fig. 3 is a view in perspective of the cutting blade mounted on the holding plate, portions being cut away to show details of construction; Fig. 4 is a cross sectional view of the knife holder and is taken on line 4—4 of Fig. 2; and Fig. 5 is a fragmentary cross sectional view similar to Fig. 4 and showing the knife in operation.

As illustrated in Fig. 1, the microtome which is chosen herein as illustrative of one of the forms of machine upon which the improved knife and holder may be used, includes a housing 10 having the customary gearing (not shown) for moving the specimen holder 11 in a vertical reciprocatory path and at the same time feeding the specimen holder 11 outwardly toward a stationary knife 12.

2

The knife holder 13 is mounted in a cradle 14 which is supported in a slide 15 seated on ways in an extended base portion of the housing 10. The slide is provided with set screws 16 arranged to clamp the cradle 14 and knife holder 13 in the adjusted position, the screws 16 being provided to support the cradle in angular relation to the specimen 17. Screws 18 releasably hold the cradle 14 against horizontal movement.

In this invention the knife holder 13 is carried by the cradle 14 instead of the massive knife conventionally mounted therein and is positioned relative to specimen 17 by the adjustments normally used. It is a particular feature of this invention that the knife holder 13 is rigid, stable, and fixed with respect to the machine and that the relatively light weight blade is firmly supported therein for eliminating vibration and flexure without reliance on massiveness.

As illustrated in Figs. 2 and 3, the knife holder 13 comprises an elongated plate 19 having a lineal rib 20 protruding outwardly from its forward face adjacent the medial axes thereof. The upper face of the rib is formed with a reentrant angle to provide a dovetail tenon for engagement with a mortise of similar form in the knife. A pair of flanges 21 are formed in the upper and lower edges of plate 19 to assure the rigidity thereof. A boss 22 of rectangular configuration protrudes rearwardly from the central portion of plate 19. The boss is drilled and counterbored for the reception of a locking member 23 embodying a head 24 formed for sliding engagement in the counterbore and a threaded shank 25 proportioned to extend beyond the face of the boss 22. The forward upper edge of head 24 is formed with an undercut ledge or hook 26 designed for engagement with the dovetail mortise in the knife.

A thumb nut 27 is threaded upon the shank 25 of the locking member, the forward end thereof being disposed in abutting relation with the boss 22. The opening for the locking member is inclined downwardly to bias the hook 26 into interlocked engagement with the ledge on the knife when the nut 27 is tightened. A helical spring 28 is seated in the counterbore intermediate the end wall thereof, and the inner face of the locking member 23.

The cutting blade 29 associated with holder 13 is formed with a hollow ground edge 30 disposed in overlying relationship with the upper curved surface of the boss 22. The portion of the blade below the ground surface is milled with a dovetail mortise defining a ledge 31 extending down-

3

wardly and outwardly for the reception of the upper surface of the rib 20. By lodging the ledge 31 on rib 20, positive alignment may be obtained without further adjustment. The lower ledge 33 receives the hook 26 of the locking member 23.

In operation, the knife holder is adjusted to support the knife forwardly of the specimen and in spaced relation thereto. The cradle is next adjusted to provide the requisite clearance angle for the knife, and the slicing operation may then be performed. Assembly of the knife 29 and knife holder 13 is accomplished by loosening thumb nut 27 and moving the locking member 23 forward in boss 22. The knife 29 can then be lodged in engagement with rib 20 and hook 26 brought into locking relation with the ledge 33 on blade 29. Further adjustment of nut 27 will draw blade 29 into rigid, supported relation with the blade holder 13.

When any particular portion of the cutting edge 30 becomes dull, release of the tension on the locking member 23 will facilitate lateral movement of blade 29 so that a sharp section of the cutting edge 30 may be brought into alignment with the specimen. The blade 29 can then be locked in the new position and further adjustment thereof will be unnecessary.

Although the foregoing description is necessarily detailed for completely setting forth the invention, it is to be understood that such specific terminology is not intended to be restrictive or confining, and that such modifications are included that may fairly come within the scope and spirit of the invention as claimed.

I claim:

1. In a microtome, an elongated plate having a front face and a longitudinal rib on said face, an elongated cutting blade having a pair of continuous longitudinal spaced apart ledges parallel to the cutting edge, one of said ledges being in complementary engagement with said rib, an arcuate upper face on said plate extending downwardly and away from said front face, an arcuate wall on said blade in register with said arcuate face on the plate and extending to said cutting edge, and clamping means operably carried by said plate engaging the face of the other ledge whereby the blade is releasably held against movement relative to the plate and positionable therealong with the arcuate wall of the blade and the arcuate surface of the plate forming a smoothly contoured surface.

2. In a microtome, an elongated plate having a front face and a longitudinal rib on said face, an elongated cutting blade having a pair of continuous longitudinal spaced apart ledges parallel to the cutting edge, one of said ledges being in complementary engagement with said rib, a boss on the rear face of said plate, said boss having an arcuate upper face extending downwardly and away from said front face, an arcuate wall on said blade in register with said arcuate face on the boss and extending to said cutting edge, and clamping means operably carried by said plate

5 and said boss engaging the face of the other ledge whereby the blade is releasably held against movement relative to the plate and positionable therealong with the arcuate wall of the blade and the arcuate surface of the boss forming a smoothly contoured surface.

3. In a microtome, an elongated plate having a front face and a laterally extending rib on said face, an elongated cutting blade having a pair of continuous longitudinal spaced apart laterally extending ledges parallel to the cutting edge, one of said ledges being in complementary engagement with said rib, and clamping means carried by the plate engaging the face of the second ledge along the length of the blade whereby the blade is releasably held against movement relative to the plate in any selected position.

4. In a microtome, an elongated plate having a front face and a laterally extending rib on said face, an elongated cutting blade having a pair of continuous longitudinal spaced apart laterally extending ledges parallel to the cutting edge, one of said ledges being in complementary engagement with said rib, and a cam lock carried by the plate engaging the face of the second ledge along the length of the blade whereby the blade is releasably held against movement relative to the plate in any selected position.

5. In a microtome, an elongated plate having a front face and a laterally extending rib on said face, an elongated cutting blade having a pair of continuous longitudinal spaced apart laterally extending ledges parallel to the cutting edge, one of said ledges being in complementary engagement with said rib, and a locking member shiftably mounted in said plate, and a hook on said member for engaging the second ledge along the length of the blade whereby the blade is releasably held against movement relative to the plate in any selected position.

6. In a microtome, a plate having two extended end portions of rectangular cross section and adapted to be received in the blade holder of a microtome, a boss extending from said plate, said boss having an upper face and a front face, a blade, a ledge on said blade for engaging the upper face of said boss to constrain the vertical movement of said blade with respect to said boss, the upper face of said ledge forming a smooth extension of the upper face of said boss, and screw means extending through said boss for clamping said blade firmly to the front face of said boss while permitting lateral movement of the blade relative to the boss.

GEORGE W. JACOBY, JR.
